FRITZ SCHRÖTER, OF BERLIN, GERMANY, ASSIGNOR TO GESELLSCHAFT FÜR DRAHTLOSE TELEGRAPHIE M. B. H. HALLESCHES, BERLIN, GERMANY, A CORPORATION OF GERMANY

PICTURE-TRANSMISSION SYSTEM

Application filed May 25, 1928, Serial No. 280,471, and in Germany June 10, 1927.

The present invention particularly relates to the reproduction of pictures and the like in television work and particularly concerns itself with, and has as its principal object, 5 that of increasing the amount of available light upon the reproduced image.

With a view to increase the luminosity of the incoming picture, in accordance with my invention the Nipkow disk at the receiver, 10 operating in synchronism with the picture scanning or exploring means at the transmitter end assumes a modified form. Instead of the disk holes having each the size of a picture element or unit and disposed along an 15 Archimedean spiral, a number of punctiform glow-discharge lamps are distributed about the disk in a manner corresponding to the usual disk holes, and of these various lamps only that particular lamp is connected in 20 the receiving circuit which happens to pass through the field of the picture.

To produce the television picture at the receiving end, according to schemes disclosed in the earlier art, a Nipkow disk is used in 25 such a manner that a field of brightness controlled in a way free from inertia is viewed through the holes in the disk. In this case the field is of the size of the entire picture and was of uniform luminous density 30 throughout. As a result, only a correspondingly small fraction of the entire light furnished by the light-control or valve means is able to pass through any given hole of the disk, and the result is that the mean brightness 35 of the perceivable picture is extremely low.

According to the disclosures of the present invention, a considerable increase in luminosity is obtained by concentrating all 40 available light upon a picture element. The fundamental scheme underlying such an arrangement of this character is shown by Fig. 1 of the accompanying drawing, while Figs. 2 and 3 illustrate special embodiments in longitudinal section of the glow-discharge or glim

lamps for carrying out the complete arrangement of Fig. 1.

Referring to Fig. 1, 1 denotes the Nipkow disk revolving in synchronism in accordance with well-known schemes with the transmitter device. The Nipkow disk rotates about the driving spindle 2. The dimensions or contour of the field of the picture is indicated by field 3 by dash lines. In lieu of the simple perforations, the similarly positioned punctiform glow-discharge lamps I, II, III, are provided. These glow-lamps are associated by leads a, b, c, with corresponding segments A, B, C, of a commutator revolving conjointly with the disk. Single-pole connection with the commutator is sufficient, since the second pole of all lamps is united with the metallic mass of the disk which is connected with the receiver amplifier by way of lead 8, the stationary slide contact 5 and slip ring 6. The stationary contact 4 feeds the amplified incoming currents alternately to the various segments A, B, C, etc., and thus to the electrodes of equal polarity of the glow-discharge lamps I, II, III, etc. As a result of this arrangement, only one glow-discharge lamp at any given instant is connected in the receiver circuit, or, to be more precise, that lamp which happens to pass through the picture field. Hence, the whole current subject 75 to the control of the transmitter is concentrated upon a single picture or surface element, whereas according to earlier schemes it had to be uniformly distributed over the whole picture surface 3.

A suitable embodiment of a punctiform glow-discharge lamp is shown by way of example in Fig. 2. Soldered in disk 1 are metallic bushes, and into the latter the glow-discharge lamps 9 are fitted in an adjustable 85 manner, the light suitably leaving through a plane-parallel window 10 secured by cement in front. Each of the lamps is furnished with a hollow cathode 11 and a co-axial anode 12 carefully insulated therefrom. By the dia- 90

phragm-like form of construction of the electrodes as shown, concentration of the discharge current and the incandescence produced thereby upon a very small area corresponding to a picture element is insured, or, in other words, a cone of rays exactly defined in its boundaries is allowed to issue from the lamp. The electrode seals or lead-ins are indicated at 13 and 14, and the lead to the anode for instance, in all of the lamps is brought to the metallic mass of the disk by soldering wire 14 at point 16. The cathode lead is brought by way of 17 to the revolving commutator.

In order to avoid lags in discharge, it may be a good plan to maintain in all lamps a very feeble auxiliary discharge which furnishes so little light that the dark portions of the picture will not be appreciably illuminated. The connection and the arrangement of such a lamp is shown by way of example in Fig. 3, where 9 denotes again the cylindrical glass bulb of the lamp, 10 the outlet window, 12 the anode having diaphragm or screen-like action, 11 the cylindrical hollow cathode with supply lead 13. Fitted over the cathode in an insulated manner is a carefully centered issuing diaphragm for the discharge current. 19 designates an auxiliary electrode for insuring a permanent auxiliary discharge upon which the amplified incoming current is superposed.

The above described scheme operates in this manner that, apart from the revolving commutator which is supplied with current from the receiver amplifier 20 by way of the stationary brush 4 and which feeds the current consecutively to the different anodes 12, there is provided a second common supply lead from an auxiliary potential source 21 by way of a slip brush 22, a slip ring and high resistance 24 to the various auxiliary electrodes 19. The return lead from the cathode 11 is brought by way of a slide contact 5 which is in contact with slip ring 6. In this arrangement, all of the auxiliary electrodes 19 of the glow-discharge lamps are connected by way of high series resistances 24 permanently with the potential source 21, with the result that in all of the lamps, a feeble current adapted to preclude lag in the discharge is caused to flow permanently from the auxiliary electrode 19 through the diaphragm hole of screen or diaphragm 18 to the cathode 11, while the current impulse furnished from the receiver amplifier 20 and causing the bright flash of the lamp at the different points of the picture flows by way of 4 and 12 to 11.

In the forms of construction of the glow-lamp in Fig. 2 and Fig. 3, the internal construction of the same, of course, must be sufficiently stable in order to offer sufficient resistance to the centrifugal action produced by rapid rotation, which is insured by con-

venient propping of the electrodes on electrode holders or anchors. For example, the diameter of the cylindrical lamp bulb, according to Fig. 2, may be chosen so narrow that anode 12 having cylindrical shape is in direct contact with the bulb wall, if necessary, with the interposition of thin layers of a sufficiently yielding substance. Since the weight of the lamps can be made very small (say, from 5 to 10 grams), the rotation of the disk being at the rate of 10 to 20 revolutions per second will not result in centrifugal forces liable to endanger or tax the solidity of the construction. The electrodes inside the glow-discharge lamps can be accurately centered. Thus, if inside the carrier bushes for the different lamps, means adapted to allow of slight displacements in the form of a well-known adjustable nature are provided, then the different light points can be so set that the picture lines in the field of the picture will be exactly fitting together.

The advantage offered by this arrangement resides in that the eye readily perceives a very luminous picture, particularly because the light rays are not made to pass first through optical means conducive to losses. The luminous points can be kept at a diameter less than $\frac{1}{2}$ mm, so that, for the purpose of reducing the dimensions of the rotating disk to the absolute minimum, the picture field can be kept within small dimensions. The picture in this case is viewed through a magnifying optical outfit which is placed in front of the disk in the direction of the view.

Instead of the form of construction comprising glow-discharge lamps as hereinbefore described, of course, also other luminous sources adapted to the object of the invention could be employed.

Having now described my invention, I claim:

1. A system for reproducing images which includes means for receiving signals corresponding to varying picture densities, a disk, a plurality of light sources arranged in spiral formation about said disk and supported thereby, means for rotating said disk in synchronism with a corresponding element at a transmitting station, means associated with said signal receiving means for sequentially flashing said light sources in accordance with said received signals, and means for maintaining a permanent biasing potential upon all of said light sources for the purpose of maintaining an auxiliary discharge and eliminating the effects of lag in the periodic flashing of said light sources.

2. A system for reproducing images which includes a disk, a plurality of light sources carried by said disk and arranged in spiral formation about the marginal portion thereof, means for rotating said disk and successively passing each of said light sources

through a predetermined image reproducing area, means for sequentially illuminating each of said light sources with a light intensity corresponding to the intensity of light and shade at the corresponding point of the image being reproduced during the period of passing each of said sources through said image reproducing area, and means for permanently maintaining a dull glow in all of 10 said light sources for eliminating the effects of lag in the periodic illumination of each of said light sources when passed through said image reproducing area.
